Primary Examiner — Terry Wallace*Assistant Examiner* — Dana L Meyrow*(74) Attorney, Agent, or Firm* — David Weiss(57) CLAIM

The ornamental design for a bottle, as shown and described.

DESCRIPTION

FIG. 1 is a front elevation view of a bottle showing our new design, the rear, left side and right side elevation views being mirror images;

FIG. 2 is a top plan view thereof; and,

FIG. 3 is a bottom plan view thereof.

The broken lines in FIGS. 1-3 illustrate the portions of the design that form no part of the claim.
